UNITED STATES PATENT OFFICE

102,171

DESIGN FOR A JAR OR SIMILAR ARTICLE

Theodore J. Piazzoli, Connellsville, Pa., assignor to Capstan Glass Company, Connellsville, Pa., a corporation of Delaware

Application October 9, 1936, Serial No. 65,224

Term of patent 14 years

To all whom it may concern:

Be it known that I, Theodore J. Piazzoli, a citizen of the United States, residing in Connellsville, county of Fayette, State of Pennsylvania, have invented a new, original, and ornamental Design for a Jar or Similar Article, of which the following is a specification, reference being had to the accompanying drawing, forming a part thereof.

Fig. 1 is a front elevational view of a jar illustrating my new design;

Fig. 2 is a side elevational view of the jar; and
Fig. 3 is a top plan view of the jar.

I claim:

The ornamental design for a jar or similar article, substantially as shown.

THEODORE J. PIAZZOLI.
